RIDING HABIT

Filed Jan. 27, 1931

INVENTOR.

Theodore Kotzin

UNITED STATES PATENT OFFICE

THEODORE KOTZIN, OF LOS ANGELES, CALIFORNIA

RIDING HABIT

Application filed January 27, 1931. Serial No. 511,505.

This invention relates to improvements in garments of the trousers variety such as used for riding, hiking, golf, etc., for men, women and for children, but more particularly for women's apparel.

One of the main objects of this invention is to provide a simple, efficient garment so constrained in use as to permit the rear seat portion thereof to be folded back upon itself to open position thereby giving access to the undergarments of the wearer, without changing the position of the front part of the trousers or of the position of the belt,—a condition which entirely eliminates the so-called "panty waists" for children.

A further object thereof is to provide a trousers garment with integral means, located at the rear upper portion thereof, and designed to allow the seat portion thereof to be pulled down to open or drop position whilst the front part of the garment is properly draped or supported around the figure of the wearer.

Another object of this invention is to provide, in a trousers garment, a quickly attachable and detachable drop seat, characterized by the feature of instant disengagement from the adjacent parts of the garment and by the simple manner of disconnecting it from the belt that may be worn about the waist line of the garment without sagging.

A still further object of the present invention is to provide a novel trouser garment especially for use by females whereby, when occasion arises for making way for exposing the posterior parts of the anatomy, it will not be necessary, as at present required, to let down the entire upper part of the garment, with the result that the contents of the pockets of the garment may fall out and with the further inconvenience of having to detach and attach the usual belt girdling the waist line of the garment.

Another purpose is to provide a trousers garment for women which, while allowing the front upper part to remain belted around the figure, will permit the quick detachment of the rear seat thereby affording the same effect, when it is necessary to expose the posterior part of the anatomy from inside the

garment, as would be the case were the entire upper part of the garment let down.

In carrying out the details of making the present garment, a trousers is provided of proper shape, drape, and disposition about the person of the wearer, with the added convenience of a detachable rear seat whose upper edge and opposing edges are quickly connected to or disconnected from the adjacent parts of the garment, without disturbing the position of the usual belt employed to secure the figure of the wearer.

With the above and other objects in view my invention consists in the combination, and details of construction disclosed in the drawing and specification, and then more particularly pointed out in the appended claim.

In the drawing, wherein similar reference characters designate similar parts throughout the respective views,

Figure 1 is a front elevation of a trousers showing the belt mounted thereupon, and showing also the quickly operable connector between drop seat and adjacent parts of the garment.

Figure 2 is a top plan view of the parts of the garment,

Figure 3 is a rear elevation of the garment with attached belt,

Figure 4 is a rear elevation of the garment showing the drop seat in open position.

It is well known that when trousers are worn by females no provision is made in the garment, when nature calls, to uncover just so much of the waist line or adjacent parts of the knickers as will lead to the desired action without the necessity of letting down the entire upper part of the garment. The present invention overcomes this shortcoming by providing a drop seat which alone need be detached from the garment when it is necessary to expose the parts of the anatomy, and which does not interfere with the belted method of maintaining the waist line of the garment about the hips of the wearer of the garment.

The trousers shown is designated broadly 10 having the usual leg portions 11. 16 designates the drop seat, the outer portion of which is designated 24. The opposing lateral edges of the drop seat carry the conventional

clasp elements 14 in a longitudinal line, while the adjacent edges of the garment, along the hip seams of the garment, also carry the inter-
5 engageable clasp elements 13, the usual make and break connectors 15 engaging both sets of clasp elements, in a manner well understood by those skilled in the art, for the purpose of quickly attaching or detaching the drop seat 16 to or from the adjacent parts or edges of
10 the garment. The upper edge 17 of the drop seat 16 is also detached from the rear upper part of the garment. When the drop seat is detached along its opposing lateral edges and upper edge of the garment it can be pulled
15 down to the position shown in Figure 4.

When the clasp elements 13 and 14 are interengaged along the hip seams of the garment then the drop seat is closed at the rear of the garment as shown in Figure 3. A belt
20 19 of conventional construction is passed through the usual belt loops 15 secured along the front part at the waist line of the garment and extends around so as to girdle the rear part of the garment, and here the belt overlaps the upper edge 17 of the drop seat 16. The terminal 22 of the belt passes through and is releasably attached to the usual buckle 21, whose tongue 20 projects adjustably through any of the usual holes formed in the
25 belt. 12 designates the usual pockets of the garment. Hooks 18 are carried upon the outer face of the upper edge 17 of the drop seat 16, in such a manner that their bills are spaced out of contact with the drop seat providing guides for the rear portion 19a of the belt as shown in Figure 3. So it will be seen that in addition to supporting or retaining the front portion of the belt at the front of the waist line of the garment, against sagging, the
30 drop seat itself has its hooks removably engaged over the upper rear edge of the belt so as to connect the belt upon the drop seat and support the drop seat upon the belt after the latter is girdled around the figure of the
35 wearer.

In operation whenever the female wearer of the garment desires to free parts of her anatomy from the rear parts of the garment, as may be accomplished without letting down
40 the entire effective upper part of the garment, all it is necessary to do is to unhook the drop seat from the belt whilst the latter still supports the front of the garment around her figure and waist line and to pull it down and back so as to fold the drop seat upon the adjacent part of the garment. The garment is now entirely open at the rear sufficiently to expose the undergarments so the latter may be manipulated to expose parts of the anatomy desired, and this takes place so whether or not the drop seat is detached or attached to the garment the pockets 12 thereof remain in up position not subjecting the contents thereof to dropping out or becoming lost, nor requiring of the wearer the tedious inconven-

ient labor of unstrapping the belt and securing it about her waist from time to time as nature calls for.

It is obvious that changes may be made in the size, shape, or making of the garment, or
70 in regard to the particular kind of fasteners employed for quickly detaching and attaching the drop seat to open or closed position and I do not intend to limit myself to the exact details of construction save as pointed out in
75 the appended claim.

What I desire to claim and secure by Letters Patent is:—

In combination riding breeches consisting of a waist portion formed buttonless at its
80 front and rear portions, means forming the back portion into a drop seat, means disposed laterally of the breeches for detachably securing the drop seat in closed relation to the breeches, a belt extending around the waist portion and overlapping the outer part of the drop seat when the latter is in closed position, loops secured around the waist portion of the breeches and accommodating the belt therein
85 adjustably, and a series of hook elements secured to the upper edge and outer face of the drop seat, so when the drop seat is in closed position the belt may be tucked under and be retained by the hook elements, and whereby when it is desired to open the drop seat the
90 hook elements may be disengaged from the belt while the latter remains intact in waist-girdling position.

In witness whereof he has hereunder set his hand this 21st day of January, 1931.

THEODORE KOTZIN.
